US0D1033396S

(12) **United States Design Patent** (10) Patent No.: **US D1,033,396 S**
(45) Date of Patent: ** Jul. 2, 2024

(54) **EARPHONE**

(71) Applicant: **ZHAOQING DEQING GRANDSUN ELECTRONIC CO., LTD.**, Zhaoqing (CN)

(72) Inventors: **Jiugao Peng**, Zhaoqing (CN); **Haiquan Wu**, Zhaoqing (CN); **Ruiwen Shi**, Zhaoqing (CN); **Shiwen Guo**, Zhaoqing (CN); **Guixiao He**, Zhaoqing (CN); **Fuhua He**, Zhaoqing (CN); **Lei Cao**, Zhaoqing (CN); **Yong Wu**, Zhaoqing (CN)

(73) Assignee: **ZHAOQING DEQING GRANDSUN ELECTRONIC CO., LTD.**, Zhaoqing (CN)

(**) Term: **15 Years**

(21) Appl. No.: **29/828,644**

(22) Filed: **Feb. 28, 2022**

(30) **Foreign Application Priority Data**

Aug. 31, 2021 (CN) 202130572893.8

(51) LOC (14) Cl. **14-01**

(52) U.S. Cl.

USPC **D14/223**

(58) **Field of Classification Search**

(57) **CLAIM**

The ornamental design for an earphone, as shown and described.

DESCRIPTION

FIG. 1 is a first perspective view of an earphone showing the new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict portions of the earphone that form no part of the claimed design.

1 Claim, 8 Drawing Sheets
